(57) **CLAIM**

The ornamental design for the leather case with keyboard as shown and described.

DESCRIPTION

FIG. 1 is a front, right, and top perspective view of the leather case with keyboard, showing my design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded perspective view thereof;

FIG. 10 is a front and top perspective view showing the leather case with keyboard a position of use; and,

FIG. 11 is another front and top perspective view showing the leather case with keyboard a position of use.

The broken lines depict portions of the leather case with keyboard that form no part of the claimed design.
